(57) **CLAIM**

The ornamental design for a jewelry box, as shown and described.

DESCRIPTION

FIG. 1 is a perspective view of a first embodiment of a jewelry box showing my new design;

FIG. 2 is a front elevational view of the first embodiment thereof;

FIG. 3 is a rear elevational view of the first embodiment thereof;

FIG. 4 is a left side elevational view of the first embodiment thereof;

FIG. 5 is a right side elevational view of the first embodiment thereof;

FIG. 6 is a top plan view thereof of the first embodiment thereof;

FIG. 7 is bottom plan view of the first embodiment thereof;

FIG. 8 is a perspective view of the first embodiment with the top cover removed;

FIG. 9 is a perspective view of a second embodiment of a jewelry box showing my new design;

FIG. 10 is a front elevational view of the second embodiment thereof;

FIG. 11 is a rear elevational view of the second embodiment thereof;

FIG. 12 is a left side elevational view of the second embodiment thereof;

FIG. 13 is a right side elevational view of the second embodiment thereof;

FIG. 14 is a top plan view thereof of the second embodiment thereof;

FIG. 15 is bottom plan view of the second embodiment thereof; and,

FIG. 16 is a perspective view of the second embodiment with the top cover opened.

The portions shown in broken lines are included for illustrative purposes only and form no part of the claimed design.
